Atty.

UNITED STATES PATENT OFFICE.

HARRY RUVIN, OF SCHENECTADY, NEW YORK, ASSIGNOR, BY MESNE ASSIGNMENTS,
TO BUXTON INCORPORATED, OF SPRINGFIELD, MASSACHUSETTS, A CORPORATION
OF MASSACHUSETTS.

KEY CASE.

Application filed December 16, 1920. Serial No. 431,137.

To all whom it may concern:

Be it known that I, HARRY RUVIN, a citizen of the United States, residing at Schenectady, in the county of Schenectady, State 5 of New York, have invented certain new and useful Improvements in Key Cases, of which the following is a specification.

My present invention relates to key cases, and more particularly to key cases of the 10 type in which a plurality of keys may be secured by independent fasteners.

The object of my invention is to provide a simple and efficient device for holding a plurality of keys in which each key will be 15 free to move independently of the others, and in which any key desired may readily be selected and separated from the other keys.

The novel features which I believe to be 20 characteristic of my invention are set forth with particularity in the appended claims. The invention itself, however, together with further objects and advantages thereof will best be understood by reference to the following description taken in connection with the accompanying drawing, in which Fig. 1 is an elevation of the key case with the flaps open; Fig. 2 is a similar view with the flaps 25 closed; and Fig. 3 is a perspective view of the key supporting member.

As indicated in the drawing, the case comprises a back member 1 with side flaps 2 and 3 which are foldable along the dotted lines. The back member and flaps are preferably of 35 some flexible material such as leather, and are preferably formed of a single piece of material. The flaps may be provided with the usual snap fasteners 4 for holding the flaps together when folded over the back 40 member, as indicated in Fig. 2.

A key supporting member 5, which is preferably of non-corrodible metal is secured to the back member 1 near one end thereof by means of rivets 6, as indicated, or in any 45 other desired manner. In the form of my invention here illustrated this key supporting member is made up of a flat plate having raised portions 7 stamped thereon, each of these raised portions being adapted to act as 50 a pivot member for a key holding device, such, for example, as the snap hooks 8 indicated.

Each one of these snap hooks is adapted

to hold one or more keys, and each hook is also free to move in more than one plane. 55 Keys held by these hooks naturally tend to lie in parallel relation to the back member. In practice also the hooks will preferably be located so close together that keys held on adjacent hooks will overlap one another. In 60 case the hooks were movable in only one plane and upon opening the case it was desired to select a key which was overlapped by those on each side thereof the key desired could not readily be lifted without at the 65 same time lifting with it the keys on each side. Because of the fact that the hooks are free to move sidewise as well as vertically, however, the disadvantage mentioned is eliminated and the keys on each side of the one 70 desired can readily turn with the hooks to which they are attached, and allow the key desired to pass between them.

While I have illustrated and described only one form of my invention, it will be 75 apparent that my invention is by no means limited to the precise construction set forth as many modifications in the particular structure employed may be made without departing from the scope of my invention as 80 set forth in the appended claims.

What I claim as new and desire to secure by Letters Patent of the United States, is:

1. A key case holder comprising a sheet-metal plate having spaced slots therein adjacent one edge of the sheet, and a plurality of straps disposed across the slots to support key holders. 85

2. The combination in a key case of a flat key supporting member having a plurality 90 of openings therein, a portion of said supporting member being raised and bridging each of these openings, said bridging portions being adapted to serve as pivots for snap hooks. 95

3. The combination in a key case of a flat key supporting member having a plurality of openings therein, a portion of said supporting member being raised and bridging each of these openings, said bridging portions being adapted to serve as pivots for snap hooks, and a series of snap hooks held 100 by said bridging portions.

In witness whereof, I have hereto set my hand.

HARRY RUVIN.
